UNITED STATES PATENT OFFICE.

WILLIAM ORR, OF MEMPHIS, TENNESSEE.

SOUND-MODIFYING MEANS FOR SOUND TRANSMITTING AND REPRODUCING MACHINES.

Application filed March 29, 1924. Serial No. 702,895.

My invention relates to sound modifying devices for instrumentalities adapted to transmit or record the sounds of the voice, such as dictating phonographic machines, 5 telephones and speaking tubes.

The objects of the invention are to provide means whereby the sound of the voice of the person speaking into the mouth piece of the instrument is prevented from being 10 audible to others near the speaker with the resulting advantage of enabling dictation and telephoning to be carried on without the disturbance of others in the same room with the speaker and insuring privacy in the recording or transmitting of the message. A 15 particularly advantageous use of the invention is in the report of proceedings in a court room or a convention by direct vocal repetition of the spoken words into the machine 20 instead of a record by stenographic notes, followed by subsequent transcription or dictation.

Another object of the invention is to clarify the tones of the voice vibrations so 25 that a clear and distinct record and reproduction of the voice sounds may be obtained.

With these objects in view, my invention is embodied in preferable form in the construction hereinafter described and illus- 30 trated in the accompanying drawings.

In these drawings—

Fig. 1 is a longitudinal section through the sound tube and mouth piece embodying the invention; and

Fig. 2, a cross section on line 2—2 of Fig. 1.

Referring to the drawings, 1 indicates the usual flexible tube adapted to extend to the sound receiving diaphragm box of a dictation recording machine. This tube may, in use in connection with a telephone, be replaced by the diaphragm holder of the telephone. Connected to and communicating with this tube 1 is a transmitter 2, comprising 45 a tubular body surrounding at one end thereof the tube 1 and formed preferably of an outer tubing 3 of rubber or other flexible material within which is secured a lining 4, preferably of a material which is a non-conductor of sound. The outer end of the barrel of the transmitter terminates in a mouthpiece 5 adapted to fit over the mouth of the speaker.

Placed loosely within the body of the 50 transmitter is a multiple funnel member,

the inner end of which projects into the inner end of the tube 1. This member consists of several tubular truncated cones 6 of tin coiled or curved circularly and of progressively increasing size from the inner to 60 the outer element and loosely nested one within the other. Two are shown but a greater number may be employed if found desirable. This device acts as a sound modifying means, its probable action being to 65 exert a drag or impedance to the resonance of the tones of the voice through the pressure of the sound waves against the tubular elements, plus a decrease in the volume of sound waves emerging from the inner end 70 of the funnel, due to its tapered or cone shaped formation.

Surrounding the inner end portion of the tube 1 is a cylinder 7, preferably of tin, which is packed with cotton or equivalent fibrous 75 material 8 which bears also against the tube 1. The space between the cylinder 7 and the barrel of the transmitter is also packed with cotton. The effect of this cotton is to 80 damp the sound waves and prevent reflection and the combined action of the multiple funnel and cotton packing is to clarify the voice so as to give a much clearer record and also produce a noisless mouthpiece.

The inner end of the space between the 85 barrel of the transmitter and the sound conveying tube 1 has a closure 9 consisting preferably of a plug of plaster of Paris. In this closure is formed a vent 10 for the escape of air expelled from the mouth of the 90 speaker. The air passes from the barrel and inner end of the funnel member into and through the cotton. This vent also permits a circulation of air through the device.

The sound waves of the voice escape from 95 the inner end of the mouth tube and from the multiple non-resonant and impedance tubular member fall on the cotton placed in the lower section of the tubing and are partly absorbed thereby.

What I claim is:

1. A transmitter for speech reproducing devices having a barrel of non-resonant material, a mouth tube, a sound conveying tube with which said mouth tube is connected, a closure between the walls of said tubes, a series of tapered coiled members of non-resonant material nested one within the other and mounted loosely within said mouth engaging tube and projecting into 100 105 110

said sound conveying tube, and a packing of fibrous material between the barrel of the mouth engaging tube and the sound conveying tube and adjacent the inner end of 5 said nested tubular members.

2. A speech transmitter comprising a tubular mouth member, a tubular element of non-resonant material axially disposed within the tubular mouth member, said tubular 10 element tapering away from the outer end of the tubular mouth member.

3. A speech transmitter comprising a tubular mouth member and a plurality of loosely nested tubular elements axially supported within said tubular mouth member 15 and tapering away from the mouth end of the tubular mouth member.

4. A speech transmitter comprising an elongated tubular mouth engaging member, 20 a plurality of nested tubular members axially supported within the mouth member, said nested tubular member being coiled in form, and formed of non-resonant metal.

5. A speech transmitter comprising an 25 elongated tubular mouth engaging member, a member axially disposed and supported within said mouth engaging member, said axially disposed member comprising a plurality of coiled cone shaped members nested

together and formed of metal and a sound 30 conveying tube extending into the end of the mouth engaging member and in which the coiled cone shaped members terminate.

6. A speech transmitter comprising a tubular mouth engaging member, a tapered 35 tubular member axially disposed and supported within the mouth engaging member and a fibrous sound damping member within the tubular mouth engaging member and adjacent the end of the tubular member. 40

7. A speech transmitting device comprising an elongated mouth engaging tubular member, an apertured lug in one end of the mouth engaging member, a sound conveying tube extending through said plug and 45 into the mouth engaging member, a sleeve surrounding said sound conveying tube in spaced relation thereto and secured to the tube, a fibrous material surrounding the tube within the sleeve, a fibrous material 50 surrounding the sleeve and interposed between the sleeve and the mouth engaging tube and an axially disposed tapered member within the mouth engaging tube and having its end disposed within the end of 55 the sound conveying tube.

In testimony whereof I affix my signature.
WILLIAM ORR.
